COMPARTMENTALIZED COOLING CUSHION
FOR PETS

Helen K. Murray, R.F.D., Gridley, Ill. 61744

Filed Mar. 6, 1969, Ser. No. 16,097

Term of patent 14 years

Int. Cl. D30—99

U.S. Cl. D30—41

FIG. 1 is a top, front perspective view of the compartmentalized cooling cushion for pets;

FIG. 2 is a bottom rear perspective view thereof similar to FIG. 1 but showing the end thereof opposite to that appearing in FIG. 1; and

FIG. 3 is a vertical, cross-sectional view through the cushion taken on line 3—3 of FIG. 1.

I claim:

The ornamental design for a compartmentalized cooling cushion for pets, as shown.
